UNITED STATES PATENT OFFICE.

HARRY C. ZIMMERMAN, OF WASHINGTON, DISTRICT OF COLUMBIA.

REGULATOR FOR RECOIL MECHANISMS OR BUFFERS.

Application filed September 16, 1924. Serial No. 738,073.

(GRANTED UNDER THE ACT OF MARCH 3, 1883, AS AMENDED APRIL 30, 1928; 370 O. G. 757.)

The invention described herein, if patented, may be manufactured and used by or for the Government for governmental purposes without the payment to me of any royalty 5 thereon.

The subject of this invention is a regulator for recoil mechanisms or buffers.

In recoil mechanisms of the hydro-pneumatic type, it has been customary to position 10 the throttling valve of the regulator assembly perpendicularly with respect to the receiving cylinder or chamber. This arrangement necessitates the fabrication of an irregular cradle body which includes the receiving 15 chamber and also requires drilling the irregular portion of the cradle to receive the transversely disposed elements of the regulator mechanism.

Obvious difficulties in forging and machining 20 and also in assembling and dismantling together with the additional weight incident thereto have led to the present improvement which contemplates disposing the valve mechanism longitudinally within the regulator body so that the assembly may readily be inserted and removed as a cartridge, while 25 greatly facilitating the forging operation in constructing the cradle. The invention, further, aims to have the valves receive from and 30 discharge into a common orifice in the regulator body, which arrangement is a great convenience in forming the regulator body of a single member for housing both the intake valve and the return valve and sleeve.

The cylinder head which holds the regulator in place is provided with an oil filling valve to permit replenishing of the oil supply 35 or reserve. For indicating the measure of the oil reserve an oil gauge is slidably carried by 40 the regulator body and the cylinder head and is adapted to be moved rearwardly by the floating piston of the counterrecoil group when the oil reserve is depleted.

To these and other ends, my invention consists in the construction, arrangement, and 45 combination of elements, described herein-after and pointed out in the claims forming a part of this specification.

A practical embodiment of my invention 50 is illustrated in the accompanying drawings, in which,

Figs. 1 and 1^a are longitudinal horizontal sectional views taken through the regulator assembly;

Fig. 2 is a transverse sectional view through 55 the cradle;

Fig. 3 is a plan view of the regulator body; and

Fig. 4 is a side elevation thereof;

Fig. 5 is a front view thereof;

Fig. 6 is a sectional view on line 6—6 of 60 Fig. 5; and

Fig. 7 is a rear view thereof.

Referring to the drawings by numerals of 65 reference:

According to the invention, a gun cradle 11 symmetrical throughout, is formed with a plurality of longitudinal chambers designated, respectively, the recoil chamber 12 which receives the piston of the recoil mechanism, the recuperator or receiving chamber 13 and the reserve chamber 14 which may be partitioned to contain both an oil and an air 70 reserve. The dividing wall between the recoil and the recuperator chambers is formed 75 with an aperture 15 so that the oil from the recoil chamber may be forced into the receiving chamber during recoil of the gun and returned thereto during counterrecoil in a 80 well known manner.

Positioned in the receiving chamber 13 is a regulator body 16 held against an annular shoulder in the chamber by a block 17, which constitutes the rear closure for the chamber. The regulator body is formed with a central 85 longitudinal bore 18 of variable diameter from which radiates an orifice 19, aligned with the aperture 15 in the dividing wall and serving to establish a rear and front section 90 of the regulator body within which the intake and return valves for the receiving chamber are located.

In the rear section is an intake throttling valve 20, formed with a collar 21 for limiting its forward movement in a liner 22. Surrounding the valve stem is a spring 23 confined between the collar 21 and a spring seat 24 which closes the bore and limits rearward movement of the valve. A pilot 25 and a bushing 26 also serve to guide the valve in 100 its movement. The valve in addition to having the conventional prongs 27 is formed with a central passage 28 having a restricted opening 29 and radially disposed ports 30 for initial throttling action while the passage 28 105 may also convey oil to the ports 31 for the purpose of lubricating the moving parts.

Passing transversely through the cut away

portion of the regulator body (Figs. 1^a, 3 and 4) is a passage 32 for establishing communication via the throttling valve between the orifice 19 and the receiving chamber.

- 5 The forward section of the bore 18 constitutes a buffer valve chamber 33 in the rear mouth of which adjacent the orifice 19 is mounted a valve body 34 having a valve seat 35 and a return or buffer valve 36. 10 Threaded into the front mouth of the chamber is a bushing 37 through which a buffer 38 on a floating piston 39 passes during the final stage of counterrecoil of the gun to restrict the opening and decrease the counter- 15 recoil velocity as the gun approaches battery. The major portion of the buffer section of the regulator body is in the form of a reduced extension centered by wings 40 and serving to increase the area of the chamber while 20 providing space for conveniently mounting an oil gauge.

The oil gauge consists of a rod 41 passing longitudinally through the rear portion and one of the wings 40 of the regulator body and 25 adapted to be moved rearwardly by the floating piston 39 when the oil reserve is depleted. A lug 42 on the rear end of the rod 41 thread- 30 edly receives an auxiliary rod 43 slidable in the block 17 and the free end of which is formed with a head 44 whose position with respect to a recess 45 in the block indicates the measure of the oil reserve. The lug which is located in the large counterbored rear end of the regulator body acts as a stop for the 35 gauge which is urged forwardly by a spring 46 confined between the regulator body and a collar 46' on the rod 41.

The block 17, held in place by a follower 47, is formed with a longitudinal passage 40 having an apertured dividing wall 48 to form a seat for a spring pressed filling valve 49 movable in a guide 50. The rear end of the 45 passage is tapped for the reception of a block 51, which is removable to provide for attachment of a pump for adding oil to the chamber. The oil is free to pass through channels 52 in the regulator body (see Figs. 3 to 7), the channels being tapped for the reception 50 of a tool for extracting the body. The rim of the rear end of the regulator body may be slotted as at 53 to provide an inlet from a communicating passage 54 leading to the oil reservoir.

During recoil of the gun, the oil in the 55 recoil chamber is forced by the piston through the aperture 15 and orifice 19 when it enters the receiving chamber through the throttling valve 20 and moves the floating piston 39 forwardly against pressure. On counterrecoil 60 the oil is forced through the buffer valve chamber 33 and is throttled by the buffer valve 36 on return to the recoil chamber through the orifice 19. During the final stage of counterrecoil, the buffer 38 enters the buffer chamber 33 to restrict the opening so that

the gun may be eased into battery. If a proper oil reserve has been established the floating piston will be stopped before striking the rod 41 of the oil gauge. Consequently, when the head 44 of the gauge remains 70 in its recess 45 it is an indication that the oil reserve is sufficient. If not sufficient, the floating piston will be moved further to the rear striking the rod 41 and extruding the head 44. 75

While in the foregoing there has been illustrated and described such combination and arrangement of elements as constitute the preferred embodiment of my invention, it is nevertheless desired to emphasize the fact 80 that interpretation of the invention should only be conclusive when made in the light of the subjoined claims.

I claim:

1. A regulating device for the flow of 85 liquid in ordnance buffers embodying a receiving chamber having an aperture, a regulator body in said chamber formed with an orifice, an intake and a return valve disposed longitudinally in said body at either side of 90 the orifice, a block for closing said chamber and for retaining the regulator body in place, a filling valve disposed longitudinally in said block, and an oil gauge passing through the regulator body and block and movable 95 therein.

2. A regulating device for the flow of liquid in ordnance buffers embodying a receiving chamber having an aperture, a regulator body in said chamber formed with an orifice, an intake and a return valve disposed longitudinally in said body at either side of 100 the orifice, a block for closing said chamber and for retaining the regulator body in place, and a filling valve disposed longitudinally in 105 said block.

3. A regulating device for the flow of liquid in ordnance buffers embodying a receiving chamber having an aperture, a regulator body in said chamber formed with an 110 orifice, an intake and a return valve in said body at either side of the orifice, a block for closing said chamber and for retaining the regulator body in place, and a filling valve disposed longitudinally in said block. 115

4. A regulating device for the flow of liquid in ordnance buffers embodying a receiving chamber, a regulator body having a common inlet and outlet orifice, an intake valve at the rear end of said orifice, a return valve at the front of said orifice, said body formed with a transverse passage leading to the receiving chamber and a longitudinal passage extending to the rear of the body, a block in rear of the regulator body, a filling valve in said block, and said block and body having adjacent counterbored portions. 125

5. A regulator including a body formed with a central longitudinal bore and having an orifice radial to said bore, an intake valve 130

in the rear section of the bore, a return valve in the front section thereof, said body also formed with a transverse passage and an intersecting longitudinal passage for establishing communication through the body.

6. A regulator including a body formed with a central longitudinal bore and having an orifice radial to said bore, an intake and a return valve in the bore at either side of the radial orifice, and said body further formed with a transverse passage for establishing an outlet for the intake valve.

7. A regulator including a body formed with an orifice, and an intake and a return valve disposed longitudinally in the body on either side thereof.

8. A regulator including a body formed with a common intake and return orifice, and an intake and return valve at either side thereof.

9. A regulator including a body having an intake and a return valve, a block for holding the body in place, means mounted for reciprocation in the block and body for indicating pressure, and means for limiting forward movement of said means.

10. A regulator including a body formed with a common intake and return orifice and an intake and return valve carried wholly within the body.

HARRY C. ZIMMERMAN.
